UNITED STATES PATENT OFFICE.

NATHAN H. DAVIS, OF PHILADELPHIA, PENNSYLVANIA.

REVERSIBLE BRAKE-BEAM STRUT.

1,163,741.

Specification of Letters Patent. Patented Dec. 14, 1915.

Application filed July 3, 1915. Serial No. 37,808.

To all whom it may concern:

Be it known that I, NATHAN H. DAVIS, a citizen of the United States of America, residing in the city and county of Philadelphia, in the State of Pennsylvania, have invented a certain new and useful Improvement in Reversible Brake-Beam Struts, of which the following is a true and exact description, reference being had to the accompanying drawings, which form a part thereof.

My present invention relates to trussed railway brake beams, and has for its object to provide a simple and effective fulcrum strut which is readily reversible, so that it may be applied to a brake beam with the brake lever, which is pivoted to the strut, inclined relatively to the beam in either of the two directions in which such levers are inclined, thus making it unnecessary to provide separate right and left hand struts. The desirability of making it unnecessary to provide separate right and left hand struts has long been recognized, and for this purpose many different forms of so called reversible struts have been proposed and some of these have gone into actual use. My improved strut differs in substantial respects, however, from all prior reversible struts of which I have knowledge.

Novel characteristics of my improved strut are its division into two parts, or members, one of which seats against the compression member of the beam, while the other seats against the tension member of the beam, and has the brake lever pivotally connected to it midway between the two ends of the member which are similar to one another and each provided with a seat adapted to engage the tension member of the beam. Provisions are made for detachably connecting the strut member seating on the compression member to either end of the brake lever carrying strut member, and the inclination of the brake lever may be reversed by turning the brake lever carrying strut member end for end.

An important novel characteristic of my improved strut construction in its preferred form, is the fact that the brake lever carrying member has suitable provisions at each end for engagement by the coöperating parts or parts of any of the common forms of what is known as a "third suspension." These provisions may well be so formed and

disposed that they do not interfere with the use of a brake beam containing them, on any of the different types of trucks on which interchangeable brake beams are commonly used.

In the accompanying drawings and descriptive matter I have illustrated and described some of the various forms in which my invention may be embodied.

Of the drawings: Figure 1 is a plan view 65 of a brake beam embodying my invention; Fig. 2 is an elevation taken on a larger scale then, and partly in section on the broken line 2—2 of Fig. 1; Fig. 3 is a partial plan 70 of a portion of the beam shown in Fig. 1, the view being taken on the same scale as Fig. 2 and partly in section on the line 3—3 thereof; Fig. 4 is a side elevation of the strut shown in Figs. 1, 2 and 3 with the two parts thereof separated; Fig. 5 is a section 75 through the strut taken on the line 5—5 of Fig. 1; Fig. 6 is a section taken similarly to Fig. 5, but with the strut reversed; Fig. 7 is a view taken similarly to Fig. 2 showing a 80 slightly modified form of main strut member; Fig. 8 is an elevation partly in section and showing the beam compression member in section, illustrating the application of my invention to a brake beam comprising a compression member of different cross section; Fig. 8^A is an elevation partly in section illustrating the use of my invention in a brake beam having no provisions for a "third suspension"; and Fig. 9 is an elevation 85 partly in section illustrating the application 90 of my improved strut to a beam comprising a compression member having still another cross section.

In the drawings, and referring first to the construction shown in Figs. 1 to 6 inclusive, 95 A represents the compression member, B the tension member or truss rod, and C the brake heads of a trussed beam of a type in common use. My improved strut connecting the central portions of the oppositely bowed compression and tension members A and B, comprises two parts, or members, D and d. The brake lever carrying strut member, or part, D has its two ends similarly shaped, each being provided with a curved seat D' shaped to fit against the truss rod B, and terminating in spaced apart bracket ears D². The ears D² at the end of the member D adjacent the truss rod in the assembled beam are curved 100 105 110

to extend over and partially embrace the truss rod B, and are formed with apertures D⁸ adapted to receive the pintle or shaft E' for connecting to the beam the beam engaging part of any ordinary "third suspension." 5 The strut member D is also formed at each end with a passage D⁴ for a bolt F employed to rigidly connect the strut member, or part, d to whichever end of the member D is presented to it. The member D is formed between its end with the brake lever slot D⁵, and alined apertures D⁶ are provided midway between the ends of the member D for the brake lever fulcrum pin.

15 The member d is shown as comprising a hollow rectangular body fitting about the compression member A, which, as shown, is of channel bar section. The member d also comprises top and bottom extensions d² and d³ which fit against the top and bottom surfaces of the end of the member D to which the part d is secured. The extensions d² and d³ are formed with bolt holes to receive the bolt F by which the strut members D 20 and d are secured together.

25 A web d⁴ connects the extensions d² and d³ to one another and to the hollow rectangular body of the member d. This web d⁴, which does not extend to the outer ends of the extensions d² and d³, has a portion of its outer edge shaped to form a stop against which the member D abuts. As shown, the curved edge d⁵ of the web d⁴ abuts against the crown of the truss rod bearing of the adjacent end of the member D. The web d⁴ thus 30 limits the approach of the member D toward the compression member A of the beam when the latter is being assembled. The frame like body of the member d, is formed 35 at its inner side with apertures d⁷ through which the ears D² project into the open side of the channel bar shaped compression member A. In assembling the beam, the walls of the apertures d⁷ serve to fix the relative positions of the members D and d in the direction of the length of the beam. Alined apertures d⁸ and d⁹ are formed in the top and bottom walls of the hollow body of the member d to receive the wedge key G by which 40 the part d is rigidly clamped to the beam compression member A.

50 In the form shown in Figs. 1 to 6, the extension d³ of the member d is curved to fit about a portion of the ears D² which projects laterally beyond the outline of the body portion of the member D. In consequence, the extensions d² and d³ must be sprung apart somewhat in connecting the members D and d to, or detaching them 55 from one another. This, of course, introduces no real difficulty when the member D is made of malleable cast iron, as is usual. Advantageously, as shown, the web d⁴ is cut away along the lines d¹⁰ and d¹¹ to facilitate 60 the insertion of the member D between the

extensions d² and d³ and its removal therefrom, and to reduce the amount to which the extensions d² and d³ must be sprung apart to permit such insertion and removal.

With the construction described it will be 70 obvious that by turning the strut member D, end for end, relative to the remaining parts of the brake beam, the inclination of the brake lever slot D⁵ and consequently of the 75 brake lever mounted therein may be made either that shown in Fig. 5, or that shown in Fig. 6, thus avoiding all necessity for separate right and left hand strut members. Inasmuch as the brake lever carrying strut member D does not directly engage the compression member of the beam, the length of 80 the member D is not fixed by the distance between the tension and compression members of the beam, but is fixed by the distance desired between either seat D' and the center line of the apertures D⁶. The last mentioned distance is required by standard rail-way practice to be less than half the distance 85 between the tension and compression members of the beam.

90 The strut as a whole is exceedingly simple, and the parts composing it are rigidly secured together and cannot get out of adjustment in operation and may readily be made of ample strength. It is a comparatively 95 easy matter to put my improved strut in place in the initial assembling of a beam, or to reverse the lever carrying strut member when this is desirable, in the case of a previously assembled beam.

100 My invention is not limited in its use to any particular type of truss beam, but may readily be designed for use in connection with many different types of truss beams; indeed to fit the great majority of truss beams now in use, it is only necessary to provide a corresponding number of compression member engaging strut parts, for at the present time most of the different types of truss brake beams in use differ from one 105 another, in so far as the application of a strut thereto is concerned, only in the cross section of the compression member of the beam. While each compression member ordinarily requires that the strut member connected to be shaped to correspond to the special cross section of the compression member, the same form of the brake lever carrying member of the strut may be used in most cases. This is illustrated by Figs. 110 7, 8 and 9. In these figures and in Fig. 8A, I have illustrated some of the changes in the form of embodiment of my invention which may be made to meet different operating conditions or to fit different brake beam designs. In Fig. 7, for instance, the main strut member DA corresponds generally to the member D hereinbefore referred to, differing therefrom only in the fact that the ears d²⁰, corresponding to the ears D² of the 115 120 125 130

member D, form a closed truss rod receiving eye instead of an open eye. The ears d^{20} , moreover, do not project laterally beyond the outline of the end of the member DA. 5 The strut member da corresponds generally to the strut member d hereinbefore referred to, differing mainly in the shape of the web portion d^{40} connecting the extensions d^{20} and d^{30} which in this construction are similar to one another.

10 In Fig. 8 I have illustrated the application of my improved strut construction to a brake beam in which the compression member AA is of U section. As shown, the strut 15 of Fig. 8 differs from that shown in Fig. 7, only in the connecting part db which replaces the part da , and is shaped to fit about the brake beam compression member AA.

The construction illustrated in Fig. 9 differs from that shown in Figs. 7 and 8 only 20 in that the compression member AB of the brake beam is an angle bar and the connecting part dc of the strut is correspondingly shaped.

25 While, as already stated, I consider it a distinct advantage of my invention that my improved strut may be readily formed with provisions for a "third suspension", my improved strut can also be used in a beam 30 not equipped with provisions for a "third suspension". In this case the eyes D^s are dispensed with, and the lever carrying member of the strut correspondingly shortened. This is illustrated in Fig. 8^A, 35 where the main strut member DB has its ends formed with a groove adapted to receive the truss rod of the beam. In this construction the connecting part dd has lugs d^{50} interposed between the adjacent end of 40 the main strut member DB and the edges of the compression member of the beam which, as shown, is of U shape as in Fig. 8.

While in accordance with the provisions 45 of the statutes I have illustrated and described the best forms of my invention now known to me, it will be apparent to those skilled in the art that other changes may be made in the embodiments of my invention disclosed without departing from the 50 spirit of my invention, and that under some conditions certain features of my invention may be used without a corresponding use of other features.

Having now described my invention, what 55 I claim as new and desire to secure by Letters Patent, is:

1. A two part fulcrum strut for a truss brake beam comprising an end for end reversible, brake lever carrying strut member having its two ends each formed with a seat for the brake beam tension member, and a second strut member formed with a seat for the brake beam compression member and adapted to be interposed between the 65 latter and the first mentioned strut member.

2. A two part fulcrum strut for a truss brake beam comprising an end for end reversible, brake lever carrying strut member having its two ends each formed with a seat for the brake beam tension member, and a second strut member formed with a seat for the brake beam compression members and adapted to be interposed between the latter and the first mentioned strut member, and means for detachably securing the two strut 75 members together.

3. A two part fulcrum strut for a truss brake beam comprising an end for end reversible, brake lever carrying strut member having its two ends each formed with a seat for the brake beam tension member and with provisions for a "third suspension" connection, and a second strut member formed with a seat for the brake beam compression member and adapted to be interposed between the latter and the first mentioned strut member.

4. A two part fulcrum strut for a truss brake beam comprising an end for end reversible, strut member having its two ends 90 each formed with a seat for the brake beam tension member, and having means for connecting a brake lever to said strut member to turn about an axis midway between the two seats of said strut member, and a second strut member formed with a seat for the brake beam compression member and adapted to be interposed between the latter and the first mentioned strut member.

5. A two part fulcrum strut for a truss 100 brake beam comprising an end for end reversible, brake lever carrying strut member having its two ends each formed with a seat for the brake beam tension member, and a second strut member formed with a seat for the brake beam compression member and adapted to be interposed between the latter and the first mentioned strut member, and being formed with a surface engaging the 105 said seat on the adjacent end of the first 110 mentioned strut member when so interposed.

6. A two part fulcrum strut for a truss 115 brake beam comprising an end for end reversible, brake lever carrying strut member having its two ends each formed with a seat for the brake beam tension member and with an extension projecting beyond said seat and embracing the tension member engaging said seat and apertured for a "third 120 suspension" connection, and a second strut member formed with a seat for the brake beam compression member and adapted to be interposed between the latter and the 125 first mentioned strut member.

7. A two part fulcrum strut for a truss 130 brake beam comprising an end for end reversible, brake lever carrying strut member having its two ends each formed with a seat for a brake beam tension member, and a

second strut member interposed between the first mentioned strut member and the compression member of the beam and comprising a portion adapted to surround said compression member and apertured to receive a portion of the adjacent end of the first mentioned strut member.

8. A two part fulcrum strut for a truss brake beam comprising an end for end reversible, brake lever carrying strut member having its two ends each formed with a seat for a brake beam tension member, and with a pair of spaced apart ears extending transversely to and projecting beyond said seat, and a second strut member interposed between the first mentioned strut member and the compression member of the beam and comprising a frame portion adapted to surround the compression member of the beam and formed with apertures in one side to receive the said ears of the adjacent end of the first mentioned strut member and formed with a portion extending away from said frame between said apertures and adapted to engage the said seat of the ad-

jacent end of the first mentioned strut member.

9. In a truss brake beam the combination with a tension member of a compression member of channel bar cross section and 30 having its open side toward the tension member, and a strut connecting the central portions of said tension and compression members, and comprising two parts, one a brake lever carrying member having its 35 two ends each formed with a seat for the tension member, one or the other of said seat engaging the tension member in the assembled beam while the other end of said strut member projects into the open side of 40 the compression member of the beam, and the other strut part interposed between the first mentioned strut member and the compression member of the beam and comprising an open ended frame surrounding said 45 compression member and apertured to permit a portion of the first mentioned strut member to project into said compression member.

NATHAN H. DAVIS.
